UNITED STATES PATENT OFFICE.

JOSEPH JAUCH, OF MERIDEN, CONNECTICUT, ASSIGNOR TO THE BRADLEY & HUBBARD MFG. CO., OF SAME PLACE.

AIR DISTRIBUTER OR SPREADER.

SPECIFICATION forming part of Letters Patent No. 603,105, dated April 26, 1898.

Application filed October 11, 1897. Serial No. 654,811. (No model.)

To all whom it may concern:

Be it known that I, JOSEPH JAUCH, of Meriden, in the county of New Haven and State of Connecticut, have invented a new Improvement 5 in Air Distributers or Spreaders; and I do hereby declare the following, when taken in connection with the accompanying drawings and the letters of reference marked thereon, to be a full, clear, and exact description 10 of the same, and which said drawings constitute part of this specification, and represent, in—

Figure 1, a view in side elevation of an air distributer or spreader constructed in accordance with my invention; Fig. 2, a view thereof in vertical central section; Fig. 3, a view thereof with the deflector and retaining-screw removed; Fig. 4, a detached plan view of the deflector; Fig. 5, a reverse plan view 20 thereof; Fig. 6, a view of the air-distributer in transverse section on the line *a b* of Fig. 1 and looking toward the deflector; Fig. 7, a similar view of the air-distributer on the line *c d* of Fig. 1 and showing the supporting and 25 centering arms; Fig. 8, a detached view of the retaining-screw; Fig. 9, a detached plan view of the washer-like current-breaker.

My invention relates to an improvement in air distributers or spreaders for Argand or 30 central-draft lamps, the object being to produce a simple, compact, and highly-effective device.

With these ends in view my invention consists in an air distributer or spreader having 35 certain details of construction, as will be hereinafter described, and pointed out in the claims.

In carrying out my invention I employ an inverted cup-like deflector, by preference 40 formed from a single piece of sheet metal and comprising, as shown, a cylindrical body *A* and a horizontal flange *A'*, the upper portion of the said body being formed, as shown, with two circular rows of perforations *a*, and the 45 flange being imperforate or solid. I may, however, choose to employ only one row of perforations, from which I find excellent results are obtained. The said deflector is supported upon a standard consisting of an air-tube *B*, 50 to which it is firmly secured by means of a retaining-screw *C*, which passes downward

through an opening *A*², formed in the center of the body *A* of the deflector, and into the internally-threaded extreme upper end of the said air-tube *B*. The upper end of the said air-tube is formed with air-ports *B'*, which are in the form of rectangular openings, as shown, but which may consist merely of round perforations, if preferred. These perforations are located just below the screw-threads 55 formed in the tube for coaction with the screw *C*. Preferably, although not necessarily, I also employ a washer-like current-breaker *D*, which is made independent of and mounted upon the air-tube *B* at a point just below the 60 air-ports *B'*, formed therein. At its lower end the tube is supported within three radially-arranged supporting-arms *E*, which support and center the device within the air-tube of a lamp; but the particular means for 65 supporting and centering the air-tube may be changed as desired, and constitute no part of my present invention. It will be observed that the air-tube is enough smaller in external diameter than the internal diameter of 70 the body of the deflector to form an annular air-chamber *F* within the deflector, the said chamber opening downward around the tube and being free for the access of air into it 75 from a point below the said flange *A'*. 80

In using my improved device air enters the deflector through the open lower end of the annular air-chamber *F* and is jetted outward through the perforations *a*, formed in the upper portion of the cylindrical body of the deflector. A smaller quantity of air also enters the lower end of the air-tube and rises and emerges through the air-ports *B'* thereof into the annular passage *E*, from which it is jetted outward through the perforations *a*. Air is 85 thus supplied to the interior of the deflector through the annular chamber *F*, which opens downward, and through the air-tube.

The function of the washer-like current-breaker *D* is to guard the lower end of the 90 air-chamber *F* against the entrance into it of air-currents of too much strength, whereby the action of the air distributer or spreader is made even and protected against drafts. I am not, as aforesaid, obliged to employ the 95 said current-breaker, but I find its use secures a superior action of the device. 100

It is to be noted that the exterior surfaces of any part of the deflector are not relied upon to give direction to the air, but that the same is jetted outward in such a manner as 5 to supply air to and assist in shaping the form of the flame by the tension which it acquires in being heated within the deflector and tube. I do not consider it imperative to take air through the air-tube as well as through the 10 annular passage, but prefer to do so; nor do I consider it necessary to form the cup in the exact manner shown, but in any form which it may assume it will be constructed with an imperforate flange with a perforate body and 15 arranged to take air from beneath into its body and jet the same outward through perforations formed in the upper portion thereof. If desired, the deflector itself may be made in more than one piece, and instead of securing 20 it to the standard by means of a screw it may be riveted, soldered, or otherwise attached thereto.

Having fully described my invention, what I claim as new, and desire to secure by Letters 25 Patent, is—

1. In an air distributor or spreader, the combination with an inverted cup-like deflector having a perforated body and an imperforate flange, of an air-tube upon which the 30 deflector is supported, which is enough smaller in external diameter than the internal diameter of the body of the deflector to form a downwardly-opening air-passage, and which is formed at its upper end with air-ports from 35 which air taken at its lower end issues into the interior of the body of the deflector from which it is jetted through the perforations therein.

2. In an air distributor or spreader, the combination with an inverted cup-like deflector having a perforated body and an imperforate flange, of an air-tube upon which the 40 deflector is supported, and which is provided at its upper end with air-ports which open into an annular downwardly-opening 45 air-passage formed between the upper end of the tube and the body of the deflector; and a screw passing through the body of the deflector and downward into the upper end of the tube for securing the deflector thereto. 50

3. In an air distributor or spreader, the combination with an inverted cup-like deflector having a perforated body formed with a centrally-arranged opening, and with an imperforate annular flange extending outwardly from its lower edge, of a tube having 55 its upper end internally threaded, supporting the said deflector, and made smaller in external diameter than the internal diameter of the body of the deflector so as to form a downwardly-opening annular passage through which air rises into the said body from which it is jetted through the perforations therein, and a retaining-screw passing downward through the central opening in the body of the 60 deflector, and entering the internally-threaded upper end of the said tube to which it secures the deflector.

In testimony whereof I have signed this specification in the presence of two subscribing 70 witnesses.

JOSEPH JAUCH.
